UNITED STATES PATENT OFFICE.

IRVING B. SMITH AND CHARLES W. DORRICOTT, OF PHILADELPHIA, PENNSYLVANIA,
ASSIGNORS TO ELECTRELLE COMPANY, OF SUMMERDALE, PHILADELPHIA, PENN-
SYLVANIA, A CORPORATION OF PENNSYLVANIA.

MUSIC-HOLDER FOR SELF-PLAYING MUSICAL INSTRUMENTS.

1,170,572.

Specification of Letters Patent.

Patented Feb. 8, 1916.

Application filed July 3, 1912. Serial No. 707,525.

To all whom it may concern:

Be it known that we, IRVING B. SMITH and CHARLES W. DORRICOTT, citizens of the United States, residing at Philadelphia, in the county of Philadelphia and State of Pennsylvania, have invented new and useful Improvements in Music-Holders for Self-Playing Musical Instruments, of which the following is a specification.

10 This invention relates to improvements in music roll holders for self-playing musical instruments, particularly pianos, and has for its object to provide means for correctly positioning in playing position in front of the keyboard, a roll holder of that type which is pivotally connected to a slide on which it is swung downwardly and then with the slide is pushed rearwardly out of sight and also out of the way of a player 15 manually operating the piano keys.

Another object of the invention refers to the contact fingers of an electrically operated instrument; the supporting bar or "comb" therefor; means for moving said comb to adjust the contact fingers to the position of the perforations in the music sheet, and a guard for the contact fingers to cover and protect the same, said fingers being very delicate and easily bent out of place 20 when changing the music roll, said guard preventing the fingers of the player, the music sheet, or any part of the player's clothing, such as a sleeve, touching the contact fingers.

30 Still another object of the invention is directed to the driving mechanism for the take-up roll and the rewind, which is strong, simple and very efficient and by means of a single lever, either the take-up or the 35 rewind are optionally thrown into gear and a brake mechanism simultaneously actuated for governing the rotation of the music sheet while unwinding.

With these and other objects in view the 40 invention consists of the novel construction, combination and arrangement of parts hereinafter described in detail, pointed out in the appended claims and illustrated in the accompanying drawings, in which—

50 Figure 1 is a perspective view of the im-

proved roll holder drawn forward to playing position in front of the keyboard of a piano. Fig. 2 is a front elevation of the roll holder partly in section with the front plate removed. Fig. 3 is a cross sectional view, on the line 3—3 Fig. 2, of the roll holder and a portion of the keyboard of a piano to which the holder is attached. Fig. 4 is a like view of the roll holder on the line 4—4 of Fig. 2. Fig. 5 is an elevation of the clutch mechanism for coupling up the rewind. Fig. 6 is an end view looking from the left of Figs. 1 and 2. Fig. 7 is a detail plan view of the driving mechanism. Fig. 8 is a perspective view of a portion of the finger rail or comb. Fig. 9 is an enlarged view of a portion of the finger rail or comb, and one set of fingers in contact with the music sheet. Figs. 10 and 11 are diagrammatic views of a set of fingers and a portion of the music sheet. Figs. 12 and 13 are views in end elevation showing the link connection between the contact-roller frame and the finger guard, certain of the parts being omitted for clearness of illustration. Fig. 14 is a detail view of the contact finger adjusting screw.

In the drawings, the letter A indicates a piano keybed of any well known construction, on the underside of which are fastened spaced rails B, grooved to receive a sliding plate C adapted to be moved back and forth beneath the keybed A in a manner well understood. Pivotally connected to the sliding plate C is a music sheet roll holder 20 from the rear of which project arms 21 pivoted at 22 to depending lugs 23 on the sliding plate C in such manner that the roll holder 20 may be swung from a position in front of the keyboard of the piano 90 to a position thereunder and back from the front by lowering said roll holder and pushing backward the sliding plate C, so that the roll holder will be out of sight when not in use and away from the knees of a person playing on the piano keys in the ordinary manner.

To properly adjust the roll holder when raised to playing position, a bracket 24 is fastened on each side plate 25, 25a of said 100

holder, each bracket having two arms 26 and 27 at a right angle to each other on the ends of which are soft cushions or buttons 28, 29 arranged to bear on the front and 5 underside, respectively, of the keybed A when the roll holder is in operative position. As thus constructed there are but four points of contact between the roll holder and the keybed, two contact points at each 10 end. By this arrangement the roll holder is held firmly and rigidly in place when playing, and "wabbling" and rattling prevented. A spring latch 30 is fastened to the roll holder in position to engage the 15 front edge of the sliding plate C and retain said roll holder when elevated. A handle 31 extends upward from the latch 30 sufficiently far to be conveniently operated by the fingers when it is desired to 20 release the roll holder.

Attached to the front edge of the sliding plate C and to a transverse rod 32 connecting the side plates 25, 25^a, is a helical spring 33 which is tensioned when the roll holder 25 is lowered and prevents the same from dropping suddenly, should it slip from the hand of the player, and swing rearwardly against the sliding plate to the injury of the roll holder. When in playing position, the end 30 of the spring 33 attached to the rod 32 is forward of its attachment to the sliding plate, but when the roll holder is swung downwardly and rearwardly the rod 32 passes under the sliding plate attachment 35 and the tension of the spring is exerted to retain the roll holder upward against said sliding plate, as clearly shown in dotted lines in Fig. 3.

The side plates 25 and 25^a are spaced 40 apart by transverse bars 32, 34 and 35 secured to said plates, the whole forming a rigid frame in which are mounted the take-up roll 36, the contact finger comb 37, the 45 comb supporting rail 38, a swinging frame 39 in which is journaled the finger contact roller 40, and a support on each of said plates for the music-sheet spool 41. The driving mechanism is carried on the plate 25 and the take-up mechanism on the 50 plate 25^a.

Journaled in bearings 42 on the plates 25, 55 25^a is a shaft 43 on which the take up roll 36 is mounted to turn independently of the shaft or with the shaft when connected thereto by a clutch of any approved type, partly shown at 44 Fig. 2. A worm gear wheel 45 is fastened on one end of the shaft 43 outside the plate 25 and a spur gear wheel 46 on the opposite end of the same 60 shaft outside the plate 25^a. A worm 47 on a shaft 48 suitably supported in bearings on the plate 25 engages the worm wheel and rotates the same through the medium of a friction disk 49 mounted on the worm shaft and 65 peripherally engaging the face of the driv-

ing pulley 50 over which passes a belt leading to a suitable motive power. When the driving pulley is rotated its friction face, preferably covered with some material 51 such as leather, turns the disk 50 and the 70 worm shaft with the worm 47, thus rotating the worm wheel and the shaft 43. The speed of rotation of the take up roll and hence the tempo of the music being played is governed by the position of the friction 75 disk with relation to the driving pulley. When the disk is near the periphery of the pulley, it rotates faster than when near the center of the same, as is evident, so to govern the speed of the disk it is made to slide longitudinally on the shaft 48 by means of a lever, called a tempo lever, the movement of which changes the position of the disk. The tempo lever 52 is here shown as pivoted on a stud 58 projecting from the outer side 80 of the plate 25, the upper end of the lever having a finger piece 53 thereon. The lower end of the tempo lever 52 has a pin and slot connection with a rocking arm 54 on which is pivoted a finger 55 engaging an annular 90 groove 56 in the hub of the friction disk 49. From the above, it is clear that when the tempo lever is moved the friction disk will slide on its shaft to and from the axis of the driving pulley 50 and thus decrease or increase the speed of the take up roll 36 and the music sheet 57.

It is desirable that the action of the tempo lever 52 be not too free, as the player is liable to move it in one direction or the other a greater distance than the music sheet calls for. To prevent this the stud 58 has its outer end 59, on which the tempo lever is pivoted, of less diameter and screw threaded. A friction washer 60 is placed on each side of the tempo lever and a nut 61 threaded on the reduced end 59 of the stud, which nut can be turned by the fingers to press the washers more or less against the tempo lever, and thus increase the force necessary to move it. The inner end of the nut 61 is counter-bored to receive a helical spring which presses at all times against the outer washer.

The spur gear wheel 46 on the end of the shaft 43 opposite that which carries the worm gear 45, will, of course, rotate with the shaft, its motion being transmitted to a pinion 62 rotatably mounted on a stub shaft 63 and longitudinally movable thereon. The longitudinal movement of the pinion 62 is a limited one, the pinion always remaining in mesh with the gear wheel 46. A sprocket wheel 64 is also mounted to rotate but not to slide on the stub shaft 63, and is connected to and disconnected from said pinion by means of a clutch 65, as the pinion is moved longitudinally on its shaft.

Journaled in the top of the side plate 25^a is a short shaft 66 having means on one end 130

to engage with and rotate the music sheet spool 41, and on the other end outside the side plate a small sprocket wheel 67 is fixed, driven by a chain 68 from the sprocket wheel 64. The shaft 66 is provided with a 5 brake disk 69 for a purpose to be hereinafter described.

Between the side plates 25, 25^a is the swinging frame 39 comprising a longitudinal bar 70 having on each end a downwardly extending leg, indicated respectively by the numerals 71 and 72, said legs being pivoted to swing on the shaft 43, beyond the ends of the take up roll 36. The legs are continued 10 above the bar 70 to form bearings 73 for the finger contact roller 40, against one end of which bears a spring finger 74 connected to the return wire 75 of the electric current. The swinging frame 39 is oscillated by a 15 resilient lever 76 fastened at its lower end to the leg 72 and extending above the edge of the side plate 25^a where it is fashioned into a finger grip 77. On the rear edge of the leg 72 is formed a cam 78 see Figs. 4 and 5 20 facing the side plate 25^a which, as the swinging frame 39 is moved to the rear, strikes the end of a pin 79 extending through the side plate and pushes it outwardly, causing a 25 plate 80 on the outer end of said pin and seated in an annular groove 81 in the hub 30 of the pinion 62 to slide the pinion toward the sprocket wheel 64 and move the clutch 65 into engagement, thus throwing the 35 rewind mechanism into operation. When playing, the swinging frame is in the position represented in full lines in Figs. 3, 4 and 12 and held in such position by means of a lock plate 82 with the front edge of 40 which the spring lever 76 engages. During the rewinding operation the swinging frame is pushed back against a stop pin to the 45 position indicated by dotted lines in Fig. 4, being held in this position by the hand of the player, but as soon as the music sheet 50 has been rewound on the spool, the lever is released and the swinging frame returns to the position indicated in Fig. 13, being retained in this position by the rear edge of the lock plate 82, where it remains while 55 changing the music sheets and until playing is to be resumed. The position of the pin 79 relative to the cam 78 is such that the rewinding mechanism is not connected up until the swinging frame is in its dotted position, the clutch 65 being uncoupled by a 60 helical spring 83 when the swinging frame returns to the position indicated in Fig. 13. The rearward movement of the swinging frame automatically disengages the clutch 65 connecting the take-up roll with its shaft 43 to permit free rotation of the take-up during rewinding operation.

When playing, the music sheet spool is free to turn as the music sheet advances, and 65 it often happens, especially during rapid

passages, that the spool turns faster than the feed of the music sheet, thus tending to loosen the turns of the music sheet on the spool, crowding the music sheet forward toward the contact fingers and endangering 70 the integrity of said music sheet by creasing, rumpling and possibly tearing it. To prevent this spool from too rapid rotation and to hold it always under an even tension while playing, a brake is provided to act on the music spool holder as the music sheet is being unwound from the spool and to release said brake during the rewind.

The brake mechanism comprises a lever 84, see Figs. 3 and 4 pivoted at 84^a on the inner face of the side plate 25^a, the upper end of said lever carrying a brake shoe 85 which bears against the periphery of the disk 69 on the spool operating shaft 66. The other and lower end of the brake lever 84 has a pin and slot connection with a link 86 pivoted to the leg 72 of the swinging frame 39. A spring 87 is employed to hold the shoe 85 against the disk 69 and also serves to move the swinging frame 39 from its rewind-position indicated by dotted lines in Fig. 4 to the music-spool-changing position shown in Fig. 13. While playing, the swinging frame and brake mechanism are in the position indicated most clearly in Fig. 4, the brake shoe bearing on the disk; but when the swinging frame 39 is moved to the rear the link 86 is drawn forward for a suitable distance without moving the brake lever because of the pin and slot connection therebetween, but just before the swinging frame reaches the dotted line position in said figure, the link rocks the brake lever and withdraws the brake shoe from the disk 69.

Extending from side to side of the roll holder 20 near the front thereof and a short distance above the tie rod 34 is a horizontal longitudinally movable rail 38 supported at each end in forwardly opening recesses 88 made in brackets 89 rigidly fastened to the inner faces of the respective side plates 25, 25^a, said rail being retained in the recesses by means of swinging latches 90 pivoted on the brackets above the rail to swing downwardly in front of the rail ends and prevent the rail from falling out of the recesses. These latches are turned up when the rail is to be removed from the roll holder. Fasted on the back of the rail 38 is a contact 115 finger supporting bar or comb 37 a little shorter than the rail and extending some distance above the same, and made of some insulating material such as wood. The top 92 of the comb 37 has a downward inclination toward its rear side, which side has formed thereon near its top a slightly projecting rib 93, the upper surface of which is continuous with the inclined top 92 of the comb. Through the top of the comb and 120

- extending below the rib 93 are a plurality of parallel slots 94 equal in number to the number of key actions to be operated. Close against the front side of the comb lie a number of spring contact fingers 95 which extend upward from near the bottom of said comb to and slightly higher than the bottoms of the slots 94, and thence each through a slot to the rear side of the comb where said fingers terminate just below the rib 93 and to the rear of the same in position to bear against the contact roller 40 on the swinging frame 39 when said frame is in its forward position, as in Fig. 3. It is to be noted that each contact finger 95 is made of several strands of preferably fine phosphor bronze wire *a*, *b*, and *c* bent rearwardly at their upper ends in the form of hooks that extend through a slot 94 in a downward direction. The terminals *d* of the bent ends of the strands *a*, *b* and *c* are conveniently arranged to produce the best results in the manner shown in Figs. 9, 10 and 11. Here it will be seen that two of the terminals are placed side by side, while the third terminal lies above and between the two and is slightly shorter, the two lower terminals being of equal length, or of different lengths as desired.
- In music sheets for automatic piano players the perforations for very short notes, such as thirty-second and sixty-fourth notes, are very short and when a single contact finger is used the length of time it is in engagement with the contact roller is exceedingly short, so much so in fact that the piano action, operated when the circuit is closed, does not fully act, with the result that no tone is produced, or, if a tone is sounded, it is thin, faint and unsatisfactory. This fault is corrected by making the strands which form a contact finger of different lengths, the contacting end of one finger being slightly in advance of the other a distance less than the length of the shortest perforation so that when the first strand closes the circuit through the perforation, before it is lifted out, the second strand enters the perforation and keeps the circuit closed sufficiently long to produce a full tone of the shortest note. The above arrangement of the contact fingers is known in the art, but in the present invention, instead of using straight strands to form fingers a group of three strands are employed for each finger with bent or hook-shaped engaging ends which lie within the grooves 94 in the comb 37, and are protected from injury by the walls thereof. The straight portions or body of the contact fingers lie close against the outer side of the comb and only the extreme ends of the fingers which engage the music sheet 57 and the contact roller 40 project beyond said comb, and these ends project from its inner side. From this

it will be evident that by making each contact finger 95 of several fine wires and bending the contact ends of said fingers so as to be protected by the slotted edge of a comb, better results are obtained and protection from injury afforded said fingers. The lower ends of the fingers pass through holes 91 in the bottom of the comb and are attached each to a circuit wire 88. Insulation of the fingers from the rail 38 is provided by placing a strip 96 of non-conducting material between them, as shown in Figs. 3 and 8.

Lateral adjustment of the contact fingers 95 is sometimes necessary to correctly position them with respect to the perforations in the music sheet. For this purpose one end of the rail 38, here shown at the left of the roll holder, is bored and threaded to receive the threaded end 97 of a rod 98 projecting outside the roll holder and fitted with a finger hold 99 for rotating said rod to move the rail carrying the comb 37 and contact fingers 95 in a longitudinal direction. The rod may be supported in any suitable way, but as shown in the drawings, a collar 100 on the rod 98 bears against the inner face of the side plate 25, and a nut 101 threaded on said rod is screwed against the outer side of the plate. A lock nut 102 bears against the nut 101 and prevents its turning.

As a protection for the rail 38, the comb 37, and the contact fingers carried thereby, a curved plate 103 is placed in front of said parts and extends from one to the other of the side plates 25, 25^a. At each end of the curved plate 103 is an inwardly projecting bracket 104 having a notch in its underside to hook over and be supported each by a pin 105 projecting from the inner face of the side plates. The lower edge of the curved plate 103 is fastened to the connecting bar 34 by screws 106 extending through slots 107 cut into the lower edge of the curved plate. By this means of attachment the curved plate may be easily removed when the contact fingers are to be inspected, by loosening said screws, thus permitting the brackets 104 to be lifted off the pins 105 and the plate from said screws.

Pivotedly connected to the brackets 104 is a curved guard 108 extending the length of the curved plate 103 designed to cover the slotted upper edge of the comb 37 and further protect the contact fingers 95 from injury when changing the music sheet. The guard 108 is connected at one end by a link 109 to the leg 71 of the swinging frame 39 so that when said frame is swung forward to playing position, as in Figs. 3 and 12, bringing the contact roller 40 to bear on the fingers 95, the guard 108 will, through the link 109, be rocked so as to uncover the upper edge of the comb 37 and assume the position indicated in said figures, but when the

frame 39 is moved in the opposite direction to rewind and insert a new music sheet, the contact roll will be carried away from the fingers 95 and the guard 108 drawn over the comb, see Fig. 13. By thus covering the comb and contact fingers, the sleeve nor any other part of the player's garments can touch said fingers.

Roll holders of this type are more or less open to the collection of dust, to prevent which and cover such parts as may be exposed, a spring roller curtain 110 is mounted in the bottom of the roll holder in position to be grasped by the hand before lowering the holder and drawn over the curved plate 103, guard 108, swinging frame 39 and back to the rear of the holder where it is fastened by hooks 111 on the curtain engaging eyes 112 on the cross bar 35. When the roll holder is drawn forward for use, the hooks of the curtain are disengaged and the curtain permitted to wind on its roller, the hook 111 thereon being fastened to pins 113 as in Fig. 3.

End caps 114 are provided to inclose the mechanism on the outer sides of the end plates 25, 25^a and are fastened to said plates by means of screws 115. These caps have the same contour as the end plates; the one inclosing the driving mechanism at the left of the machine carries an index plate 116 for the tempo lever 52, and has an opening in its side for the rail adjusting rod 98 to pass through.

Having thus described the invention what we claim as new is:

1. In a device of the character described, a slidable member adapted to be mounted below the key bed of a musical instrument, a roll holder connected to said slidable member and arranged to swing up in front of the key bed to playing position, and means on said roll holder to bear against the front face of the key bed to position the roll holder.

2. In a device of the character described, a slidable member adapted to be mounted below the key bed of a musical instrument for movement back and forth thereunder, a roll holder pivotally connected on the slid-
able member to swing up in front of the key bed into playing position, a latch to lock said roll holder in playing position, and angle pieces fixed on said roll holder having portions arranged to contact respectively with the bottom and front face of the key bed to position the roll holder when raised.

3. In a device of the character described, a slidable member adapted to be mounted below the key bed of a musical instrument for movement back and forth thereunder, a roll holder pivotally connected on the slid-
able member to swing up in front of said key bed above the plane of the slidable

member into playing position, a latch to lock the roll holder when raised, and resilient means between the roll holder and the sliding member for preventing the roll holder falling when the latch is disconnected.

4. In a device of the character described, a slidable member adapted to be mounted below the key bed of a musical instrument for movement back and forth thereunder, a roll holder pivotally connected on the slid-
able member to swing up in front of said key bed above the plane of the slidable member into playing position, means for retaining said roll holder in playing position, and a spring connected to the roll holder and to the slidable member serving the double purpose of preventing the roll holder from falling when the latch is disconnected, and retaining said roll holder against the underside of the key bed when moved thereunder.

5. In a device of the character described, a slidable member adapted to be mounted below the key bed of a musical instrument, a roll holder pivotally connected to said slidable member and arranged to swing up in front of said key bed above the plane of the slidable member into playing position, angle pieces on said roll holder each adapted to bear at one point only against the front and underside of the key bed and hold the roll holder rigidly in playing position, a latch on the roll holder for locking it in playing position, and a spring to assist in raising said roll holder to playing position and prevent the same from dropping suddenly while being lowered.

6. In a device of the character described, a slidable member adapted to be mounted below the key bed of a musical instrument, a roll holder movably connected to said slidable member and arranged to be swung up in front of said key bed to playing position, means for retaining the roll holder in said position, and a resilient connection between the roll holder and the said slidable member for preventing the roll holder from falling when the retaining means is disconnected.

7. In a device of the character described, a slidable member adapted to be mounted below the key bed of a musical instrument, a roll holder pivotally connected to said slidable member and arranged to swing up in front of the key bed to playing position, means on said roll holder to bear against in front of the keyboard to playing position, the roll holder, and a yieldable connection between the roll holder and said slidable member.

8. In a roll holder for self-playing musical instruments, a frame, a take-up roll, music sheet spool supports and sound-controlling mechanism mounted in said frame, and

a spring-actuated curtain journaled in said frame for covering the parts mounted therein, said curtain arranged to be drawn around said parts and its end secured at the rear of the roll holder frame.

9. A roll holder for self-playing musical instruments, embodying a frame, carrying a tracker, a take-up roll, and end bearings for a music spool, a spring-actuated curtain mounted in the bottom of the frame

Copies of this patent may be obtained for five cents each, by addressing the "Commissioner of Patents, Washington, D. C."

and adapted to be drawn over the front of the same and be attached to the rear thereof.
